SHIFTABLE HINGE MOUNTING FOR GARMENT SUPPORTS

Filed Dec. 11, 1939

UNITED STATES PATENT OFFICE

2,217,105

SHIFTABLE HINGE MOUNTING FOR
GARMENT SUPPORTS

Hans P. Danielsen, Racine, Wis., assignor to
Hartmann Trunk Company, Racine, Wis., a cor-
poration of Wisconsin

Application December 11, 1939, Serial No. 308,659

1 Claim. (Cl. 16—171)

This invention relates to improvements in shiftable hinge mountings for garment supports, and more particularly to a hinge arrangement for the luggage or garment tray of a piece of wardrobe luggage.

The present invention is concerned particularly, although not exclusively, with that type of hand luggage wherein there is a garment tray or support preferably arranged with hangers and other devices to compactly accommodate in folded condition garments such as suits, coats and the like, as exemplified in the Bracken Patent No. 1,842,578. Heretofore, in a wardrobe case or container, the tray or garment support was removably mounted in an upper portion of the body section of the container by having its lower corner portions lodged on brackets or cleats within the container section. No attempt was made to hinge the tray with the result that it was at all times disconnected relative to the container and had to be bodily removed if access to the lower portion of the container section was desired, it being inconvenient and impractical to tilt or swing the tray when it was lodged within the container section.

It is, therefore, a primary object of the present invention to provide, in a tray equipped wardrobe container, an improved hinge mounting for the inner end of the tray, whereby the tray may be swung or tilted relative to its compartment to expose or close said compartment.

A further object of the invention is to provide a hinge mounting for a garment tray which is disconnectable, whereby the tray may be bodily removed from the garment container with which it is normally associated.

A further object of the invention is to provide a shiftable hinge mounting for a garment tray which will permit the tray to shift or be displaced outwardly in a perpendicular direction relative to the bottom wall of the container section in which it is housed to accommodate an excess amount of clothing and traveling paraphernalia within said case section.

A further object of the invention is to provide a garment tray hingedly associated with the body section of a wardrobe case and arranged for swinging movement into the vertically disposed cover of the case when the case is open, the hinge connection being such that its axis may be shifted relative to the inner end of the cover to locate the hinged end of the tray either partially within the open cover or exteriorly thereof, thereby adapting the tray to the proper

accommodation of garments confined between it and the cover of the case.

A further object of the invention is to provide a shiftable hinge mounting for a wardrobe case tray which will always insure proper and central location of the tray relative to the section of the case in which it is housed.

A further object of the invention is to provide a shiftable hinge mounting for a wardrobe case tray which will permit the tray to be pivotally swung into the open cover of the case, but which will prevent joint swinging of the cover and tray toward their closed normal positions unless the hinged inner end of the tray is in a specific projected position relative to the cover of the case.

A further object of the invention is to provide a shiftable hinge mounting for garment supports with which the commercial forms of tray equipped wardrobe cases may be readily provided, which is strong and durable, which is inexpensive to manufacture and install, and which is well adapted for the purposes described.

With the above and other objects in view, the invention consists of the improved shiftable hinge mounting for garment supports, and its parts and combinations as set forth in the claim, and all equivalents thereof.

In the accompanying drawing in which the same reference characters indicate the same parts in all of the views:

Fig. 1 is a vertical sectional view through an open tray equipped wardrobe case in which the tray is connected to the body section of the case by the improved shiftable hinge mounting;

Fig. 2 is a fragmentary detail sectional view illustrating in enlarged form a part of the showing in Fig. 1 and showing the position of the tray and the hinge elements when the tray is in its normal inner position relative to the body section of the case;

Fig. 3 is a similar enlarged fragmentary detail sectional view showing the position of the tray and the hinge elements when the tray is shifted outwardly relative to the body section of the case for greater accommodation of garments within said body section of the case;

Fig. 4 is an enlarged fragmentary detail sectional view showing the tray swung from its normal position to a substantially vertical position coextensive with the open cover of the case, the hinge mounting being in the position of Fig. 2 whereby the hinged end of the tray is offset from the inner end of the cover of the case;

Fig. 5 is a fragmentary detail sectional view illustrating the position of the tray when it is

raised into the cover and when the hinge connection is shifted so as to project the inner end of the tray toward the inner end of the cover;

Fig. 6 is a detail sectional view taken on line 5 6—6 of Fig. 2; and

Fig. 7 is a similar detail sectional view only showing a hinge mounting disconnected from the tray in a manner to permit bodily removal of the tray from the wardrobe case.

10 Referring now more particularly to the drawing in which the invention has been shown, by way of illustration, as being applied to a piece of wardrobe hand luggage, it will appear that, the cover section 10 of the wardrobe case has its inner end 15 hingedly connected to the body section 11 of the case, as at 12. Foldable stays 13, pivotally connected to adjacent inner portions of the cover and body sections, limit the opening movement of the cover relative to the body section of the case, 20 as disclosed in the drawings. When the cover of the case is open, with the body of the case lying in a flat or horizontal position, the cover is disposed in a plane perpendicular to the bottom wall of the body section.

25 The inner side walls of the body section 11 of the case, near the upper corner portions, are provided with tray supporting brackets 14. Said brackets are adapted to have seated thereon a garment tray, designated generally by the number 15. This tray is formed of any suitable material and includes a bottom 16, side walls 17, and a rear wall 18. Looped straps 19 forming handles may be secured to the side walls 17 to facilitate lifting or moving the tray 15 relative to the 30 body section 11 of the wardrobe case. Normally the tray is supported partially within the body section 11 of the case in the position shown in Figs. 1 and 2. The tray may carry suitable garment supporting and folding fixtures in the usual 35 manner.

40 The invention resides particularly in the provision of improved shiftable hinge mounting means for the inner end portion of the tray relative to the upper inner end portion of the body section 11 of the case. Each of the inner side walls of the body section of the case at the rear or inner ends thereof and adjacent the rearwardly disposed brackets 14, carries an upstanding spring metal plate 20. Only the lower or inner ends of 45 the plates are secured or anchored and the same are yieldable. The outer ends of the plates are bowed or turned outwardly as at 20' for convenience in engaging and manually manipulating the same. Each plate, inwardly of its portion 20', 50 carries an inwardly projecting trunnion 21. The adjacent outer corner portions of the inner ends of the side walls of the tray carry slotted brackets 22 with the trunnions 21 being adapted to normally lodge within the elongated slots 23 of said 55 brackets 22.

60 When it is desired to mount the tray 15 within the body section 11 of the case, the tray is supported on the brackets 14 and initially the yieldable plates 20 are flexed outwardly and are then 65 allowed to assume their normal positions with the trunnions 21 lodged within the slots 23 of the brackets 22, thereby pivotally or hingedly connecting the inner end of the tray to the inner side wall portions of the body section of the case.

70 This is the position the tray will normally assume and will remain in this position unless the body section of the case is overloaded and upward or outward shifting of the tray is necessitated. With the tray mounted in the manner described the 75 trunnions 21 are disposed within the upper ends

of the slots 23 as shown in Figs. 1 and 2. From this position the tray may be swung to an upwardly tilted position with its outer end within the outer end of the open cover section 10 of the case. This arrangement is disclosed in Fig. 4 and 15 it will be noted that the hinge mounting for the tray causes the lower end of the tray to be offset from the lower end of the cover 10. When the tray is thus swung to a substantially vertical position, ready access may be had to the interior of the body section of the case without the necessity of bodily removing the tray. If the tray is rather 20 amply packed, the offset position of it illustrated in Fig. 4 permits it to clearly accommodate garments confined between it and the cover 10. 15

At this point it should be observed that when the cover and tray are in the position of Fig. 4, it is not possible to jointly close the cover and tray relative to the body section of the case. The offset arrangement of the tray causes it to bind 25 against the cover as the cover is swung toward closed position. The cover and tray may, however, be jointly swung toward closed position by shifting the hinge connections for the tray from the position of Fig. 4 to the position of Fig. 5. 25 This will relocate the inner end of the tray relative to the inner end of the cover and will eliminate the binding action heretofore referred to.

If it is necessary to overpack the body section 30 of the wardrobe case, the improved hinge mounting for the tray will permit the tray to be pushed upwardly or outwardly relative to the case section 11. The trunnions 21 will then shift downwardly in the slots 23 and the tray will rise or telescope outwardly relative to the case section 11, as best shown in Fig. 3. The tray may be pivoted or swung to an open position from either the position of Fig. 2 or the position of Fig. 3 with equal effectiveness or from any intermediate position.

If it is desired to bodily remove the tray 15 40 from the wardrobe case, this may be readily accomplished in the manner illustrated in Fig. 7. It is only necessary to flex the spring arms 20 slightly outwardly to disengage the trunnions 21 from the bracket slots 23, and then the entire tray 45 may be separated from the wardrobe case.

From the foregoing description it will appear that the improved hinge mounting for a wardrobe case tray provides for ready attachment or detachment of the tray relative to the wardrobe case. 50 When the tray is attached it may be effectively hinged or swung relative to the case section in which it is mounted, and the hinge connections are free to shift to relocate the tray relative to the body section of the case or relative to the cover section of the case, and this is effective in adapting the position of the tray to the amount of garments contained in either the body section of the case or the tray. The hinge connection for the tray furthermore insures proper and central locating of the tray relative to the body section of the case after each movement of the tray. The improved hinge mounting is furthermore of simple and novel construction and is well adapted for 55 the purposes set forth.

60 What is claimed as the invention is:

In a luggage case including a body section, a hinged cover and a tray telescopically mounted within the body section, hinge connections between adjacent wall portions of the body section and the tray to permit movements of the tray relative to the body section comprising, yieldable trunnions mounted on said relatively immovable body section, and slotted brackets mounted on said movable tray, any portions of the slots of said 65

brackets being normally engaged by said trunnions and permitting vertical and pivotal movements of the tray relative to said body section, the trunnions being shiftable in said bracket slots in any connected and mounted position of the tray to relocate the axis of pivotal movement of

the tray, the yieldable trunnions being manually disengageable from said slotted brackets and permitting entire detachment and removal of said tray from said case body section.
